TUBE CUTTING TOOL

Willard M. Davenport, Odessa, Tex.

Application December 17, 1937, Serial No. 180,305

4 Claims. (Cl. 82—4)

This invention relates to a cutting tool and has more particular relation to that type of cutting tool specially designed for removing the riveted or overturned ends of boiler tubes preparatory to removing the same.

An object of the invention is to provide a cutting tool of the character described specially designed to be anchored to a boiler tube, or similar tube, and including means whereby the end of the tube, riveted over the sheet forming a wall of the furnace, may be removed preparatory to removing the tube for repairs.

It is another object of the invention to provide a cutting tool of the character described having novel means for feeding the cutter to the work, as well as novel means for anchoring the tool to the work.

A further object of the invention is to provide a tool of the character described which is of very simple and sturdy construction and which may be easily handled and applied to the work.

While the invention has been specially designed for use in cutting boiler tubes it may be used for other similar purposes.

With the above and other objects in view the invention has particular relation to certain novel features of construction, operation and arrangement of parts, an example of which is given in this specification and illustrated in the accompanying drawings, wherein:

Figure 1 shows a side view of the tool, partly broken away.

Figure 2 shows a longitudinal, sectional view as applied to the work.

Figure 3 shows a cross-sectional view taken on the line 3—3 of Figure 2.

Figure 4 shows a fragmentary, sectional view of the jaw operating handle and associated parts.

Figure 5 shows a cross-sectional view taken on the line 5—5 of Figure 2.

Figure 6 shows a cross-sectional view taken on the line 6—6 of Figure 2, and

Figure 7 shows a cross-sectional view of another embodiment taken on the line 5—5 of Figure 2.

Referring now more particularly to the drawings wherein like numerals of reference designate the same parts in each of the figures, the numeral 1 designates a tubular mandrel one end of which 50 has the slotted tubular cage 2 therearound, said cage having the slots 3 through which the wedge-shaped gripping jaws 4 work. The outer surfaces of these jaws are toothed to securely engage the tube to be cut. The inner sides of these jaws 55 are tapering and ride against the correspondingly

tapered faces 5 on the outside of the mandrel, said jaws having a dovetailed connection with the mandrel as shown in Figure 6. Extending axially through the mandrel there is a rod 6 and secured to one end of the rod there is a cap 7 on to which the cage 2 is threaded. The other end of the mandrel is outwardly threaded as at 8. There is a cutter head 9 rotatably mounted on the mandrel and having the oppositely arranged cutters 10, 10 mounted therein and adjustably secured in position by means of the clamp bolts 10a as shown in Figure 1. The head may be rotated by the worm gear 11 which is keyed thereon and which is in mesh with and rotated by a worm 12 whose shaft 13 is extended for connection with a suitable motor, not shown. The worm 12 and its shaft 13 may be housed within a suitable gear case 13a which is bolted to a suitable housing 13b which is splined on the mandrel and which encloses the gear 11, as shown in Figure 2. A nut 14 is screwed on to the threaded end 8 of the mandrel and has a swiveling connection with the gear case 13b whereby the head 9 and cutters 10 may be fed to the work. The nut 14 has suitable spaced sockets 14b to receive a manipulating rod 14c for turning said nut. A pair of links 15 are pivoted, at one end, to the threaded end 8 of the mandrel and between the outer ends of said links and threaded on to the outer end of the rod 6 there is a trunnion block 16 having the laterally extended trunnions 17, 17. There is an operating handle 18 whose operative end is provided with a yoke 19. This yoke comprises side plates which embrace the block 16 and in which the trunnions 17 have bearings. A cross-pin 20 extends transversely through the yoke, eccentrically with respect to the trunnions 17 and the outer ends of the links 15 have bearings on the ends of said cross-pin.

In use the end of the mandrel, carrying the cage 2, is inserted into the boiler tube 21. When so inserted the handle 18 will be swung into parallel relation with the rod 6, as shown in Figure 4 whereby the rod 6 and cage 2 will be moved into position to hold the jaws 6 retracted or out of engagement with said tube 21. The handle 18 may then be swung into right angular position relative to the rod 6 as shown in Figures 1 and 2. This will operate to exert a pull outwardly, or to the left, as shown in Figure 2, moving the cage 2 and the jaws 4 in a corresponding direction, said jaws moving upwardly and outwardly on the faces 5 into engagement with the tube 21 thus anchoring the tool in place. The motor may then be started causing the cutter head 9 to ro-

tate and the cutters 10 may then be fed to the work by turning the feed nut 14 in an appropriate direction and the overturned or riveted end 22 of the tube will be cut away to permit a removal of the tube from the supporting partition 23. The handle 18 may then be swung around to its former position as shown in Figure 4 thus moving the rod 6 inwardly, or to the left and thus retracting the jaws 4 to permit the removal 10 of the cutters from the tube.

As illustrated, in Figure 7, a slightly modified form of cutter head 9a is shown in which the cutters 10a are mounted for radial adjustment. The cutters 10a are clamped against the shims 15 24 of the clamp bolts 25 and said cutters 10a may be adjusted by adding or removing the shims 24 in an obvious manner. This is desirable as it may be necessary to adjust the cutters 10a inwardly so as to cut out the end of the tube 21 in 20 the opening of the partition 23 or so as to ream out and smooth said opening in the course of completing the repairs. This cutter head 9a, if used, is mounted on the mandrel 1 in the same manner as the cutter head 9, as shown in Figure 25 2.

It will be noted that the rod 6 is adjustable. By an appropriate turning of said rod it may be adjusted relative to the trunnion block 16 so as to, in effect, control the effective length of said 30 rod. If the effective length of the rod is shortened the jaws 4 may ride further up on the diverging faces 5 so as to engage a larger tube 21 and if the effective length of the rod 6 is lengthened, the jaws will engage a tube of smaller 35 diameter. This adjustment may also be effected by the adjustment of the cap 7 and the cage 8 attached to said cap for a like purpose.

The drawings and description disclose what is now considered to be a preferred form of the invention by way of illustration only, while the broad principle of the invention will be defined by the appended claims.

What I claim is:

1. A cutting tool comprising a mandrel one end 45 of which is shaped to enter a tube, tube engaging means on said end of the mandrel, an adjustable axial rod extended through the mandrel and connected to said tube engaging means, a lever and trunnion block on the other end of the mandrel for actuating said tube engaging means into tube engaging position or into retracted position, a cutter head rotatable on the mandrel, cutters on the head, means for rotating the cutter head and cutters and means for manually feeding the 50 cutters to the work.

2. A cutting tool comprising a tubular mandrel one end of which is shaped to enter a tube, tube engaging jaws associated with said end, a rod 55 slideable through the mandrel one end of which is operatively connected with and adapted to move said jaws into engaging relation with the tube

and the end of the mandrel, means connecting the other end of the rod and the mandrel, a cutting head rotatable on the mandrel, a gear connected to one end of said head, cutters on the other end of the head, means for driving said gear, a support for said driving means slidably mounted on said mandrel, means for preventing rotation of the supporting means relative to the mandrel, means for moving the cutter member toward the pipe engaging means comprising a member having internal threads engageable with the mandrel, said member, supporting means and head being positioned in abutting relationship on the mandrel moves the head toward the jaws. 10 15

3. A cutting tool comprising a tubular mandrel one end of which is shaped to enter a tube, tube engaging jaws associated with said end, a rod slideable through the mandrel one end of which is operatively connected with and adapted to move said jaws into engaging relationship with the tube and the end of the mandrel, means connecting one end of the rod and mandrel and adapted to move the rod whereby the jaws are moved into engagement with the tube, a cutting head rotatable on the mandrel, a gear connected to one end of said head, means for driving said gear, a support for said driving means slidably mounted on said mandrel, means for preventing rotation of the supporting means relative to the 25 mandrel, means for moving the cutter member toward the pipe engaging means comprising a member having internal threads engageable with the mandrel, said member supporting means and head being positioned in abutting relationship 30 whereby rotation of the nut on the mandrel moves the head toward the jaws. 35

4. A cutting tool comprising a tubular mandrel one end of which is shaped to enter a tube, tube engaging jaws associated with said end, a rod 40 slideable through the mandrel one end of which is operatively connected with and adapted to move said jaws into engaging relationship with the tube and the end of the mandrel, means connecting one end of the rod and mandrel and 45 adapted to move the rod whereby the jaws are moved into engagement with the tube, a cutting head rotatable on the mandrel, a gear connected to one end of said head, a gear container slideable on the mandrel, a worm in said container in mesh with said gear, means for preventing rotation of the gear container relative to the mandrel, means for moving the cutter head toward the pipe engaging means comprising a member having internal threads engageable with the 50 mandrel, said member, container and head positioned in abutting relationship whereby rotation of the member on the mandrel moves the head toward the pipe engaging means. 55

60 WILLARD M. DAVENPORT.
